UNITED STATES PATENT OFFICE.

JOHN LATERRA AND FRANK JOY, OF PATERSON, NEW JERSEY.

BANJO HAND REST.

Application filed January 13, 1927. Serial No. 160,938.

This invention relates to a novel accessory for use in connection with banjos and similar stringed musical instruments.

The invention has more particular reference to what we propose to refer to as a banjo handrest, that is, a device to be mounted upon the banjo in a position to serve as a rest for the hand carrying the customary pick.

One aim is to produce a structure of this kind which is somewhat more simple and inexpensive than the one represented in our co-pending application for patent, designated by Serial No. 156,151, filed December 21, 1926, and entitled Banjo hand rest.

Briefly, the invention has reference to a plate of smooth configuration, adapted to occupy the space between the bridge and the ordinary string anchoring means and to overlie a portion of the strings, together with a novel attaching device therefor constructed to fit upon a conventional type of banjo.

Other features and advantages of the invention will become apparent from the following description and drawings.

In the drawings:

Figure 1 is a fragmentary perspective view of a banjo showing the strings, anchoring means, and the novel handrest associated therewith.

Fig. 2 is a top plan view of the article, per se.

Fig. 3 is a side elevation showing the parts separated.

In the drawings, the reference character 1 designates the head of the banjo, 2 the rim, 3 the resonator, 4 the strings, 5 the bridge, and 6 the anchoring device for the strings. This device is of customary construction.

The attachment or hand rest is generally designated by the reference character 7 and it comprises a flat metal plate 8 of appropriate gauge metal formed integral with the bight portion of a U-shaped member 9. The arms of this member terminates in reduced screw threaded shanks 10 adapted to thread

into sockets formed in the ends 11 of the retaining bolts 12. The ends 11, being at 50 the top, are directed at right angles, and just below these, the bolt is formed with hooks 13 to engage the rim in the manner represented in the drawings.

The bolts are of course screw threaded at 55 their lower ends and retaining nuts 14 are carried thereby. In practice the plate is placed over that portion of the strings represented in Fig. 1, thus allowing the arms and inwardly directed end portions of the 60 bolts to straddle the string anchoring device 6. The method of use of the invention will be clear to persons familiar with instruments of this character. In view of this, a more lengthy description is thought un- 65 necessary.

Minor changes in shape, size and arrangement may be resorted to within the scope of the adjoined claims.

Having thus described our invention, what 70 we claim as new is:—

1. A handrest for a stringed musical instrument of the class described in the form of a plate to overlie a predetermined portion of the strings, and attaching means for 75 said plate, said attaching means comprising a U-shaped member to the bight portion of which, one end of said plate is integrally connected, and a pair of retaining bolts for said member.

2. As a new product of manufacture, a banjo handrest comprising a plate, a substantially U-shaped member to the bight portion of which said plate is integrally connected, the arms of said member terminating 85 in screw threaded shanks, retaining bolts having their upper ends directed to overlie the head of the banjo and provided with screw threaded sockets for reception of said shanks, said bolts being provided with hooks 90 to engage the upper edge of the rim of the banjo.

In testimony whereof we affix our signatures.

JOHN LATERRA.
FRANK JOY.
